Primary Examiner — Katherine A Holbrow
Assistant Examiner — Riya Salil Kamat(57) **CLAIM**

The ornamental design for a dumbbell rack, as shown and described.

DESCRIPTION

FIG. 1 is a front, right and top perspective view of a dumbbell rack showing my new design;
 FIG. 2 is a rear, left and bottom perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top plan view thereof;
 FIG. 8 is a bottom plan view thereof;
 FIG. 9 is an enlarged partial view of FIG. 1; and,
 FIG. 10 is an enlarged partial view of FIG. 1.
 The broken lines in the figures illustrate portions of the dumbbell rack that form no part of the claimed design. The dash-dot broken lines in FIGS. 1, 9, and 10, depict the boundary of the detail views and form no part of the claimed design.
